SEWING MACHINE ATTACHMENT

Richard J. McFalls and Rolland Herrington,
Troy, N. Y., assignors to Cluett, Peabody & Co.,
Inc., Troy, N. Y., a corporation of New York

Application June 12, 1940, Serial No. 340,011

14 Claims. (Cl. 112—151)

This invention pertains to sewing machine attachments and relates more especially to an appliance designed to facilitate the back seaming or "stitching-down" of a collar to a shirt body.

In accordance with usual practice a collar is secured to a shirt in two successive steps. First, the rear ply of the neckband of the collar is arranged in contact with the outer surface of the shirt body and, together with the lining of the band, is secured to the material of the shirt body by means of an ordinary sewed seam which leaves the marginal portions of said rear ply, lining and body portion projecting at one side of the seam. Secondly, these margins of the rear ply and lining of the neckband and the shirt body, which project beyond the first seam thus formed, are turned inwardly so as to lie within the confines of the finished collar as defined by said first seam. The fold formed in turning in this marginal material is closely adjacent to the seam. Then the front ply of the neckband is laid over these inturned margins and its edge (previously hemmed) is stitched to the shirt body by a second seam disposed parallel to but slightly below the first formed seam.

In performing this second step, the prior practice has been for the operator, with her fingers, to turn the marginal material inwardly just in advance of the formation of the stitches of the second seam. However, this second seam must be accurately located so as to engage the extreme edge of the front ply of the neckband and to lie very close to and parallel with the first seam, and the proper positioning of the front ply for engagement by the needle and the concomitant turning-in of the marginal material is more than the operator can do as a continuous uninterrupted procedure. Thus, in practice, the operator usually has to stop and start the sewing machine a substantial number of times in forming the second seam. In fact this seam is usually made in a series of steps, the operator stopping the machine after a few stitches, turning in the margin for a short distance ahead of the needle, and then stitching down this portion of turned-in material, and then again stopping the machine again and so on.

The present invention has for its principal object the provision of an attachment for a sewing machine designed to assist the operator in performing the second of the above steps, and in particular to provide an attachment which automatically turns in the marginal material as the sewing operation progresses. A further object

5 is to provide an attachment which not only turns in the marginal material but which also constitutes a guide or gauge to assist the operator in locating the second seam closely adjacent to the free edge of the front ply of the collarband and the accurate location of such seam closely adjacent to the first formed seam.

10 Since the shirt forms a bulky irregular mass of material somewhat difficult to handle in sewing, it is sometimes necessary for the operator to lift the presser foot slightly during seam formation in order to slide the work laterally, and a further object of the invention is to provide a work-turning and guiding attachment such as 15 above referred to which is automatically lifted so as to free the work whenever the presser foot is lifted.

20 During the initial and final stages of the formation of the second or back seam the attachment cannot be used since the extreme ends of the neckband form sharp arcs about which the seam must extend and where the space is too small to admit of the use of the attachment. A further object of the invention is to provide an 25 attachment of this kind so devised that it may readily be moved to an inactive position where it will not interfere with the free manipulation of the work in sewing around the ends of the band, but from which it may easily and quickly be 30 moved to the operative position.

35 A usual practice in attaching collars requires that the same operator perform the first step above described and then later perform the second step. Usually the operator will perform the first step upon a substantial number of collars, for example a dozen or more, before starting the second operation. Since the first step involves the mere formation of a simple sewed seam during which the attachment is not used at all, it is 40 desirable to have the attachment completely removed from the field of view of the operator at this time, and a further object of the invention is to provide means whereby the attachment may be moved to and held at a substantial distance 45 from the stitching point and out of the operator's direct vision but so that it may quickly and accurately be restored to the working field when desired. Other and further objects and advantages of the invention will be pointed out herein- 50 after in the following more detailed description and by reference to the accompanying drawings wherein:

Fig. 1 is an elevation of the attachment, viewed from the left-hand side and illustrated as applied to a sewing machine of conventional type, cer-

tain parts of the machine being shown in order to indicate the relative position of the attachment when in operation;

Fig. 2 is a front elevation of the attachment, that is to say, as viewed by the operator;

Fig. 3 is a plan view of the attachment, the presser-foot bar of the sewing machine being shown in section;

Fig. 4 is a view of the lower part of the attachment as seen from the right-hand side;

Fig. 5 is a bottom plan view of the folding portion of the attachment;

Fig. 6 is a perspective view of a lever which forms part of the support for the folding device;

Fig. 7 is a perspective view of an arm also forming a part of the support for the folding device;

Fig. 8 is an edge elevation, to larger scale, showing the folding plate removed from the other parts;

Fig. 9 is a diagrammatic plan view showing portions of a collar and shirt and illustrative of the operation of the improved folding device, the front ply of the neckband of the collar being broken away;

Fig. 10 is a view similar to Fig. 9 but showing the folding device operatively positioned and with the front ply of the neckband disposed with its edge in engagement with a guide forming part of the attachment;

Fig. 11 is a diagrammatic plan view illustrating the first step in attaching a collar to a shirt, the front ply of the neckband being turned back and a part of the lining being broken away to show the rear ply;

Fig. 12 is a section on the line 12—12 of Fig. 11;

Fig. 13 is a fragmentary diagrammatic plan view showing the appearance of the collar and shirt at the completion of the collar-attaching operation; and

Fig. 14 is a fragmentary section, to large scale, on the line 14—14 of Fig. 13.

Referring first to Figs. 11 to 14, inclusive, the numeral 1 designates the upper part of a shirt body and 2 designates the collar, the latter being provided with the neckband 3. This neckband comprises the rear ply 4 and the lining 5. In the first step of attaching the collar to the shirt (Figs. 11 and 12) the neckband is laid flat against the outer surface of the body portion 1 with the rear ply 4 of the neckband in contact with the material of the shirt body, and the several parts are then united by means of a sewed seam 6. This seam 6 is spaced inwardly a short distance from the raw edges of the several plies of material, thus leaving the projecting margin 7.

During the formation of this seam 6 the front ply 8 of the neckband is turned back as illustrated in Fig. 11, the raw edge of this front ply 8 having first been turned in to form a hem 9 whose plies are united by the sewed seam 10.

As above described, the second and final step in securing the collar to the shirt comprises the disposal of the marginal materials 7 (Fig. 14) of the several plies 1, 4 and 5 so that this marginal material lies within the confines of the neckband, and then the hemmed edge of the front ply 8 is turned down to cover this marginal material, and the front ply of the collar is secured to the shirt by a second sewed seam 12 (Fig. 14) which lies very close to the fold of the hem 9 and which is parallel to and just

below the first seam 6. The arrangement of the several constituent plies in the completed shirt is diagrammatically indicated in Fig. 14, it being noted that the marginal material 7 is disposed between the lining 5 and the front ply 8 of the neckband.

The present invention provides an attachment designed to facilitate the turning in of this marginal material and the formation of the second seam 12 at the proper location.

Referring now to Figs. 9 and 10, the attachment is illustrated as comprising the turning member or plow F, the gauge G and the guide D. These parts are disposed with reference to the sewing machine presser foot P and the needle N

as illustrated in Figs. 9 and 10. In the formation of the seam 12 the operator first turns in the marginal material at the extreme end of the neckband in the usual way by hand and starts the seam at the extreme end of the band and carries it around the curved end of the band and for a short distance, for example approximately two inches inwardly away from the end of the band. The folding member or plow F is then disposed substantially as shown in Fig. 9 upon the marginal material which has already been turned in by the operator, the left-hand longitudinal edge of the gauge G being disposed substantially in the line of the first seam 6. The operator then turns the front ply 8 of the neckband down (Fig. 10) over the upper surface of the folding member or plow F so that the extreme edge E of the front ply contacts the left-hand face of the guide D. The machine is now again started and as the work is fed by the sewing machine feed mechanism the plow or folding element F progressively turns inwardly the marginal material of the shirt body, rear ply and lining of the neckband, so that the operator is relieved of the duty of turning this material in during the progress of forming the seam. As the work feeds along, the left-hand edge of the gauge G continues to contact the folded material substantially in the line of the seam 6, the fold of the material forming a shoulder with which the gauge contacts. Likewise the extreme edge E of the front ply is kept by the operator in contact with the guide D and assuming that this guide is properly positioned with reference to the path of movement of the needle the formation of the second seam 12 closely adjacent to the extreme edge E of the front ply and parallel to and spaced by a short distance from the seam 6, is assured. This automatic folding of the marginal material continues until the opposite end of the neckband has nearly been reached whereupon the operator lifts the attachment from the work and completes the formation of the seam 12 in the usual way, by hand, it being noted that the ends of the neckband are too narrow to admit of the use of the attachment at these points.

Returning now to Figs. 1 to 8, inclusive, the folding device or plow F is illustrated as consisting of a piece of sheet metal disposed substantially horizontally, that is to say, parallel to the work-supporting surface of the bed plate of the sewing machine and having the inclined work-engaging edge 13 which constitutes the folding element. By engagement with the marginal material of the neckband this edge 13 progressively turns such material over as the collar is fed along by the feed mechanism of the sewing machine. This folder element F has a substantially flat, horizontal upper surface 14, but the rear margin

of the member F is rounded or beveled off, as shown at 15, to facilitate its entry between the several plies of the neckband. Likewise the lower forward edge of the folder F is preferably rounded off as shown at 16 to facilitate the movement of the work past this edge. However, it is not necessary to round off this edge 16 as the device will operate satisfactorily even though this edge be a sharp right angle.

To the under side of this folder F the gauge G is fixedly secured, for example, by brazing, though the parts may be integral. This gauge is of substantially rectangular transverse section, having the rectilinear edge surface 17 which is designed to engage the fold of the turned-in marginal material and which lies substantially in the vertical plane of the seam 6. This gauge G projects downwardly below the under surface of the folder F and its bottom face overlies the material of the shirt body during the sewing operation.

The folder F comprises the extension portion 18 (Fig. 5) which extends to the right of the gauge G (as viewed by the operator) and which is provided with a pair of parallel slots 19 extending transversely with respect to the line of stitch formation and which receive screws 20 by means of which the folding device F, with the gauge G, is adjustably secured to a horizontal member 21 (Fig. 2) forming a part of the edge guide D. By the provision of the slots 19 and screws 20 the folder F with the gauge G may be adjusted transversely with reference to the guide D. This guide D comprises a part having a vertical surface 22 of substantial length from front to rear and which constitutes the guide for the extreme edge E of the front ply of the neckband as above described.

The guide D is secured to a horizontal member or foot 23 of a supporting bracket 24 by means of screws 25 (Fig. 3) which pass down through an elongate slot 25^a in the part 23 and into screw-threaded openings in the horizontal member 21 of the guide D. By the provision of the slot 25^a and the screws 25 the guide D together with the folder F and the gauge G may be adjusted toward and from the presser foot P. When the parts are properly positioned, the left-hand surface 17 of the gauge G is disposed just to the left (as viewed by the operator) of the line L (Fig. 3) which designates the line of stitch formation.

While the several adjustments above described are desirable, it is contemplated that the folder F, the gauge G, the guide D and the bracket 24, may be made integral.

The bracket 24 is provided with a pair of parallel flanges 24^a (Fig. 4) which receive between them the lower end portion of a supporting arm 26. This arm (Fig. 6) is provided with an elongate slot 27 which receives the shank portion of a screw having a large flat head 28, the shank portion of the screw having threaded engagement with the body portion of the bracket 24. The head 28 of this screw is of sufficient diameter to overlap the edges of the flanges 24^a with which it contacts, thus together with the flanges, forming a vertical guideway in which the part 26 is free to slide. A spring 29 arranged within the slot 27 bears at one end against the upper end of the slot and at its other end against the shank of the screw, thus tending to force the bracket 24 downwardly with reference to the arm 26, but permitting the folder to rise and

fall in accordance with variations in thickness of the work.

The arm 26 is preferably bent at 30 (Fig. 6) to provide an upper portion 31 which is inclined to the vertical, such upper portion having an opening 32 for the reception of a pivot pin and having the angularly disposed end surfaces 33 and 33^a respectively.

The upper part 31 of the arm 26 is pivotally connected to the forward end 34 of a lever 35 (Fig. 7). The end 34 of said lever is provided with an opening 36 which receives a pivot pin 37 which also passes through the opening 32 and pivotally unites the arm 26 to the lever 35. If desired this pivot pin may comprise a projecting portion 38 (Fig. 2) shaped to form a handle for the convenient manipulation of the parts.

A flat spring 39 (Figs. 1 and 3) overlies the upper edge of the end portion 34 of the lever 26, being secured to the lever 35 by means of a screw 40. The free end of this spring alternatively contacts the end surfaces 33 or 33^a of the arm 26 and is adapted to hold the arm 26 in either of two selected positions of adjustment with respect to the lever 35, one of such positions being indicated in dotted lines at 41 in Fig. 1, while another of such positions is shown in full lines in Fig. 1.

The lever 35 is twisted intermediate its ends as shown at 42 so that while its end portion 43 is disposed in a vertical plane its portion 34 is inclined to the vertical. The part 43 of the lever 35 is provided with an opening 44 for the reception of a pivot pin and the end of the part 43 is provided with two angularly disposed surfaces 45 and 45^a respectively.

A block 46 (Figs. 1, 2 and 3) having a vertical opening for the reception of the presser foot bar B, is secured at the proper position upon the bar B by means of a set screw 47. To the right-hand side of this block 46 the part 43 of the lever 35 is secured by means of a pivot pin 48 (Fig. 3). The block 46 is furnished with a stop 49 (Fig. 3) to limit upward swinging movement of the lever 35, and a flat spring 50, secured by a screw 51 to the rear side of the block 46, has its free end designed for alternative engagement with the surfaces 45 and 45^a of the lever 35, thereby to hold the lever in either of two selected positions, one such position being shown in full lines in Fig. 1, and the other position being shown in dotted lines at 52 in the same figure.

During the operation of forming the seam 12, the attachment occupies the position shown in full lines in Fig. 1, with the folder F, the gauge G and the guide D arranged as shown in Fig. 10 with respect to the work. However, when the end portion of the neckband is to be stitched, the arm 26 is swung upwardly about the pivot pin 37 to the position indicated in dotted lines at 41 in Fig. 1, thus raising the folding and guiding devices from the work. By reason of the angular position of the forward end 34 of the lever 35, this upward swing of the arm 26 moves the folding mechanism out of the direct line of vision of the operator so that it does not seriously interfere with the stitching of the end of the neckband, although it is not raised very far from the plane of the work and is thus in a position such that it may quickly be moved down to the operative position. Thus there is no delay in placing the folder in position in readiness to continue the formation of the seam.

However, during the formation of the first seam 6, when it is desired to keep the vicinity of the

needle as free from obstruction as possible, the lever 35 may be swung up to the position indicated in dotted lines at 52 in Fig. 1, thus carrying the folding device completely out of the field of operations. During this movement the folder moves upwardly and to the right away from its operative position, thus leaving the bed plate of the sewing machine wholly free for manipulation of the work and carrying the folder entirely out of the line of vision of the operator. Since the block 46 is fixed to the presser-foot bar B, the lifting of the latter to permit entry of the work beneath the foot, also lifts the folder plate F and associated parts.

While one desirable embodiment of the invention has been illustrated by way of example, it is to be understood that the invention is not necessarily limited to this precise arrangement but is to be regarded as broadly inclusive of any and all equivalent constructions such as fall within the terms of the appended claims.

We claim:

1. A sewing machine attachment for use in back seaming a collar having the rear ply of its neckband already attached to a shirt body by a sewed seam, said attachment constituting a unit comprising supporting means secured to the presser foot bar of the sewing machine, turning means carried by said supporting means and including a plate designed to overlie the bed plate of the sewing machine in spaced relation to and in advance of the presser foot, said plate having an oblique edge operative progressively to turn in the marginal material of the rear ply and shirt body, the upper surface of said plate constituting a support for the margin of the front ply of the collarband, a gauge member secured to and projecting below the lower surface of said plate and having a straight edge which defines the line of fold in the material which is being turned, and a part projecting above said plate having a rectilinear surface constituting a guide for the edge of the front ply of the neckband.

2. A sewing machine attachment for use in back seaming a collar having the rear ply of its neckband already attached to a shirt body by a sewed seam, said attachment constituting a unit comprising turning means operative progressively to fold in the marginal material of said rear ply and the shirt body as the work is fed toward the needle of the sewing machine, a block having provision for securing it to the presser-foot bar of the sewing machine, a lever having one end pivotally secured to the block, a spring operative to hold said lever in either of two selected positions, an arm having one end pivotally secured to the other end of said lever, a spring operative to hold said arm in either of two angular positions relative to the lever and in each of which positions the turning means is raised from the work, and means attaching said turning means to the other end of said arm.

3. A sewing machine attachment for use in back seaming a collar having the rear ply of its neckband already attached to a shirt body by a sewed seam, said attachment constituting a unit comprising turning means operative to turn in the marginal material of said rear ply and the shirt body, a part having provision for securing it to the presser-foot bar of the sewing machine, a lever having one end pivotally secured to said part, a stop for limiting swinging movement of the lever in one direction, a spring operative to

hold said lever in either of two selected positions, said lever swinging in a vertical plane but being twisted so that its free end is in an inclined plane, an arm pivotally secured to the free end of said lever so as to swing in an inclined plane, a spring operative to hold said arm in either of two selected positions relative to the lever, and means attaching said turning means to the free end of said arm.

5 10 4. A sewing machine attachment for use in back seaming a collar having the rear ply of its neckband already attached to a shirt body by a sewed seam, said attachment constituting a unit comprising supporting means secured to the

15 presser foot bar of the sewing machine and including turning means operative to fold in the marginal material of said rear ply and the shirt body, a bracket to which the turning means is normally fixed, said bracket having a vertical guideway,

20 an arm having one end thereof arranged to slide in said vertical guideway, said arm having an elongate slot therein, a part passing through said slot and so connecting said arm to the bracket as to permit free sliding of the

25 bracket relatively to the arm, and a spring operative at all times to urge the bracket toward the end of the arm thereby to keep the turning means in yielding contact with the work regardless of the thickness of the latter.

30 5. A sewing machine attachment for use in back seaming a collar having the rear ply of its neckband already attached to a shirt body by a sewed seam, said attachment constituting a unit which comprises a folding plow provided with

35 a work-engaging surface operative progressively to fold in the marginal material of said rear ply and the shirt body as the work is fed toward the sewing machine needle, a block provided with means for attaching it to the presser foot bar

40 of the sewing machine, a lever pivotally secured at one end to said block, an arm having one end pivotally secured to the other end of said lever, and means attaching the turning plow to the free end of said arm.

45 6. A sewing machine attachment for use in back seaming a collar having the rear ply of its neckband already attached to a shirt body by a sewed seam, said attachment comprising a folding plow having a substantially vertical work-

50 engaging surface which extends obliquely across the line of the proposed seam and which is operative progressively to fold in the marginal material of said rear ply and the shirt body as the material is fed toward the sewing machine needle, said plow having an under surface which rides upon the folded material, and means for securing the attachment to the presser foot bar of the sewing machine.

7. A sewing machine attachment for use in back seaming a collar having the rear ply of its neckband already attached to a shirt body by a sewed seam, said attachment including a part having provision for securing it to the presser foot bar of the sewing machine, and comprising

65 turning means operative progressively to fold in the marginal material of said rear ply and the shirt body as the material is fed toward the sewing machine needle, a guide for the edge of the front ply of the neckband, a gauge operative to determine the line of fold formed by the fold-in marginal material, and means uniting the several parts of the attachment.

70 75 8. A sewing machine attachment for use in back seaming a collar having the rear ply of its neckband already attached to a shirt body by a

sewed seam, said attachment including a part provided with means for securing it to the presser foot bar of a sewing machine and comprising turning means operative progressively to fold in the marginal material of said rear ply and the shirt body as the material is fed toward the sewing machine needle, said turning means being constructed and arranged to constitute a rest for the front ply of the neckband, a guide for the edge of said front ply, and means adjustably connecting the turning means and guide, said connecting means being designed and arranged to permit relative movement of the edge guide and the turning means transversely of the line of the proposed seam.

9. A sewing machine attachment for use in back seaming a collar having the rear ply of its neckband already attached to a shirt body by a sewed seam, said attachment comprising turning means including a substantially horizontal plate having a work-engaging edge which normally extends diagonally across the line of the proposed seam and which is operative progressively to fold in the marginal material of said rear ply and the shirt body as the material is fed toward the sewing machine needle, and means operative to support said plate in operative relation to the path of movement of the work toward the sewing machine needle, said supporting means including relatively movable parts so constructed and arranged as to permit the folding plate to rise and fall freely in response to variations in thickness of the folded material.

10. A sewing machine attachment for use in back seaming a collar having the rear ply of its neckband already attached to a shirt body by a sewed seam, said attachment including a block having provision for securing it to the presser foot bar of a sewing machine and comprising turning means including a plate supported by said block and which, in use, is located above the bed plate of the sewing machine in advance of the presser foot and which rides upon the folded-in marginal material of said rear ply and shirt body as said folded material advances toward the needle, said plate having an oblique work-engaging edge operative by engagement with said marginal material progressively to turn the latter in and form a fold, a gauge projecting below the lower surface of said turning plate, and means operatively connecting the gauge and plate, the gauge having an elongate substantially vertical surface parallel to the line of feed and which is operative to define the line of fold.

11. A sewing machine attachment for use in back seaming a collar having the rear ply of its neckband already attached to a shirt body by a sewed seam, said attachment comprising turning means including a folding plate which, when in use, is located above the bed plate of the sewing machine in advance of the presser foot and which rides upon the folded-in marginal material of said rear ply and shirt body as said folded material approaches the needle, the upper surface of said folding plate sloping downwardly toward that end of the plate which is nearest to the presser foot, said upper surface constituting a support for the front ply of the neckband, the front edge of said plate extending obliquely across the line of the proposed seam and being operative progressively to fold in the marginal material,

said oblique edge being smoothly rounded at its lower corner thereby to facilitate the entry of the work beneath it, and means for securing the attachment in operative relation to the sewing machine presser foot and needle bar.

5 12. A sewing machine attachment for use in back seaming a collar having the rear ply of its neckband already attached to a shirt body by a sewed seam, said attachment including a part having provision for attaching it to the presser foot bar of a sewing machine with the attachment located in advance of and spaced from the presser foot, the attachment comprising turning means operative progressively to fold in the marginal material of said rear ply and the shirt body as the material is fed toward the needle, the supporting means including relatively movable parts operative to permit free rise and fall of the turning means in accordance with varying thicknesses of the folded material, and spring means yieldingly urging the turning means downwardly toward the work.

10 13. A sewing machine attachment for use in back seaming a collar having the rear ply of its neckband already attached to a shirt body by a sewed seam, said attachment comprising a normally substantially horizontal folding plate arranged in advance of and spaced from the presser foot of the sewing machine, said plate having an upright work-turning edge extending obliquely across the line of the proposed seam and operative progressively to fold in the marginal material of said rear ply and the shirt body as the material is fed toward the machine needle, the under surface of said plate riding upon the folded-over marginal material, and the upper surface of the plate being arranged to support the front ply of the neckband, and connections operative to attach the folding plate to the presser foot bar of the sewing machine, said connections being so constructed and arranged as to permit the folding plate to be moved to and held in either of two inactive positions, each at a substantial distance above the bed plate of the sewing machine.

15 14. A sewing machine attachment for use in back seaming a collar having the rear ply of its neckband already attached to a shirt body by a sewed seam, said attachment including means for securing it to the presser foot bar of the sewing machine and comprising work-engaging means normally disposed in advance of the presser foot and needle, said work-engaging means including a folding plow operative to fold in the previously 20 united margins of said rear ply of the neckband and the shirt body, said plow having a substantially vertical folding surface extending obliquely across the line of the proposed seam and having a substantially flat under surface which rides upon the folded-in marginal material as the work progresses toward the presser foot, a gauge element disposed below the plane of said flat under surface of the plow and designed to engage the edge of the formed fold, and a guide element located above the upper surface of the plow and operative to engage and guide the edge of the front ply of the neckband, and means operatively uniting the plow, the gauge and the guide.
